(21) Appl. No.: **29/259,074**

The ornamental design for a cap for anchor on tilt-up concrete slabs, as shown and described.

(22) Filed: **May 3, 2006**

DESCRIPTION

(51) **LOC (8) Cl.** **12-05**

FIG. 1 is perspective view of a cap for anchor on tilt-up concrete slabs showing our new design;

(52) **U.S. Cl.** **D34/35**

FIG. 2 is an exploded view thereof;

(58) **Field of Classification Search** D34/28,

FIG. 3 is another exploded view thereof;

D34/35, 33; 294/82.35, 75, 82, 34, 82.36;

FIG. 4 is a perspective view of one of the halves of the cap;

52/125.5, 125.6

FIG. 5 is an elevational view of the front thereof;

See application file for complete search history.

FIG. 6 is a bottom plan view thereof;

(56) **References Cited**

FIG. 7 is a side elevational view thereof;
